UNITED STATES PATENT OFFICE.

STENGRIM ALSETH, OF OSAKIS, MINNESOTA, ASSIGNOR OF ONE-THIRD TO HANS P. OLSON AND ONE-THIRD TO RUDOLF STROM, BOTH OF OSAKIS, MINNESOTA.

CAROUSEL.

1,360,071.

Specification of Letters Patent. Patented Nov. 23, 1920.

Application filed February 5, 1920. Serial No. 356,505.

To all whom it may concern:

Be it known that I, STENGRIM ALSETH, a citizen of the United States, residing at OSAKIS, in the county of Douglas and State 5 of Minnesota, have invented certain new and useful Improvements in Carousels, of which the following is a specification.

The invention relates to a carousel and more particularly to the class of portable 10 merry-go-rounds.

The primary object of the invention is the provision of an apparatus of this character wherein the same is constructed of a size so that it can be placed either indoors or out 15 doors and when indoors can be located within a room so that children may operate the same, the power for its operation being imparted thereto by levers actuated from the seats of the objects, simulating hobby- 20 horses, the actuating mechanism being of novel form to eliminate excessive leverage in the working of the levers for imparting power to the turn-table of said apparatus.

Another object of the invention is the provision of an apparatus of this character 25 which is novel in construction so that the riders will be afforded amusement in the use thereof and the speed of travel of the same can be varied at the option of the 30 riders, the apparatus being of miniature type so that it may be placed for use in comparatively small space and the riders will impart the requisite motion for the working of the apparatus.

A further object of the invention is the provision of an apparatus of this character 35 wherein continuous rotary motion can be imparted thereto and the operating mechanism being of a form to withstand strains and hard usage.

A still further object of the invention is the provision of an apparatus of this character which is comparatively simple in construction, neat and attractive in appearance, 45 readily and easily operated, strong, durable and inexpensive to manufacture.

With these and other objects in view the invention consists in the features of construction, combination and arrangement of 50 parts as will be hereinafter fully described, illustrated in the accompanying drawing and pointed out in the claims hereunto appended.

In the accompanying drawing:

55 Figure 1 is a top plan view of the carousel

or merry-go-round constructed in accordance with the invention.

Fig. 2 is a vertical sectional view thereof.

Similar reference characters indicate corresponding parts throughout the several 60 views in the drawing.

Referring to the drawing in detail, the merry-go-round or carousel comprises a base 5 preferably of circular contour, although the same may be made in any other shape 65 and in this instance is constructed from wood, although other material may be employed should it be found desirable. Covering the top face of the base 5 is a metal plate 6 correspondingly shaped to said base 70 and is fastened thereon in any suitable manner, the plate being designed to serve as a traction bed.

Fixed to and rising vertically centrally from the base 5 is a center post 7, the lower 75 end being formed with a securing flange 8 which is fixed to said base in any suitable manner.

Adapted to revolve about the center post 7 is a cross beam 9 to the opposite ends of 80 which are connected the trucks 10 for supporting objects 11 simulating in this instance hobby-horses, yet the same may imitate other conventional toys, the trucks being supported upon caster wheels 12 which 85 travel upon the traction plate 6 as is clearly shown in Fig. 2 of the drawing.

Surrounding the center post 7 and fixed to the crossbeam 9 is a tube 13, the opposite ends being formed with flanges 14 and 15, 90 the former being suitably secured to the beam 9 while secured to the flange 15 is a gear 16 adapted to rotate with the trucks 10 and through this gear motion is imparted to the latter through actuating mechanism and 95 in a manner hereinafter fully described.

The objects 11 simulating hobby-horses are provided with seats 17 for occupancy, the seats being reversely disposed for the reason that the riders of the hobby-horses or occupants of the seats face the direction in which the trucks travel as one truck follows the other in the rotary course thereof, the beam 9 holding the trucks 10 diametrically opposite upon the base 5 at all times.

100 The operating mechanism comprises a ratchet toothed disk or member 18 stationarily mounted upon the center post 7 superposed relative to the gear 16, the disk or member being formed with a central hub 19 110

forming a rest for one of a pair of superimposed bridging yokes 20 loosely journaled in overlapped relation to each other upon the upper end portion of the center post 7 and held in such relation through the medium of a nut 21 threaded on said upper end of the post 7, the yokes being connected to swinging operation levers 22 arranged diametrically opposite relative to the gear 16 and each has formed on its inner end a toothed sector 23 meshing with the teeth of the gear 16, while the outer end of said lever extends forwardly of the seat 17 upon the object 11 on that side of the gear adjacent to said lever. Each lever 22 is connected with the yoke 20 through the medium of the pivot bolt 24 so that the lever has independent swinging movement relative to the yoke 20 which also is adapted to swing upon the center post 7 in the operation of the merry-go-round or carousel.

Carried on and pivoted to each yoke 20 is a ratchet pawl 25 which is adapted for locking engagement with the respective teeth of the disk or member 18 to retard movement of the yoke in one direction while said yoke is free for movement in the opposite direction and the pawl 25 thereon during this movement will ride over the teeth of the disk or member 18, the handle end 26 of the lever 22 being manually actuated by the occupant of the seat 17 or the rider of the object 11 so that motion can be imparted to the trucks 10 for the rotation thereof in one direction. The handle end 26 of each lever when pulled upon rocks the lever 22 and the meshing engagement of the sector 23 with the gear 16 causes the latter to be rotated and through the instrumentality of the tube 13 rotary motion is imparted to the trucks 10. On pulling the levers 22 a predetermined distance the same are moved in a retrograde direction or pushed upon, thus advancing the yoke 20 so as to change the position thereof relative to the disk or member 18 to advance the lever 22 for the next pulling action thereon and in this manner a continuous rotary movement is imparted to the trucks for the rotary travel thereof upon the base 5 of the apparatus or carousel.

On each lever 26 adjacent to the pivot 24 is a stop 27 which is adapted to engage the yoke 20, when the said lever 26 is pushed forward, thereby limiting its advanced movement relative to the yoke 20, and this causes both the latter and the lever to move in unison on further advance of the said lever.

It will be clearly apparent that the merry-go-round or carousel is manually operated and power is imparted thereto by the riders of the objects 11 or the occupants of the seats 17 so that the trucks 10 will be advanced, the varying exertion of the riders

or occupants will correspondingly vary the speed of travel of the truck in the rotary movements thereof.

From the foregoing it is thought that the construction and manner of operation of the apparatus will be clearly understood and therefore a more extended explanation has been omitted.

What is claimed is:—

1. An apparatus of the character described comprising a base, rotary objects supported thereon, a stationary vertical center post rising from the base about which the objects revolve, a gear connected with the objects and rotatable upon the post, a ratchet disk fixed to the post above the gear, operating levers movably supported relatively to the post and having toothed sectors meshing with the gear, a swinging connection between the levers and ratchet pawls carried by the swinging connections of the levers and co-operating with the ratchet disk.

2. An apparatus of the character described comprising a base, rotary objects supported thereon, a stationary vertical center post rising from the base about which the objects revolve, a gear connected with the objects and rotatable upon the post, a ratchet disk fixed to the post above the gear, operating levers movably supported relatively to the post and having toothed sectors meshing with the gear, a swinging connection between the levers, ratchet pawls carried by the swinging connections of the levers and co-operating with the ratchet disk, and wheeled trucks supporting the objects and movable upon the base.

3. An apparatus of the character described comprising a base, rotary objects supported thereon, a stationary vertical center post rising from the base about which the objects revolve, a gear connected with the objects and rotatable upon the post, a ratchet disk fixed to the post above the gear, operating levers movably supported relatively to the post and having toothed sectors meshing with the gear, a swinging connection between the levers, ratchet pawls carried by the swinging connections of the levers and co-operating with the ratchet disk, wheeled trucks supporting the objects and movable upon the base, a connection between the trucks to hold the same opposite each other, and a tube surrounding the post and connecting the gear with said connecting means between the trucks.

4. An apparatus of the character described comprising a support, trucks movable over the support, a stationary center post rising from the support, means revolvable about the post and connected with said trucks, manually operable oscillatory levers for imparting motion to said revolvable means, a stationary member on the post means connected with the manually operable

levers and having ratchet engagement with the stationary member to hold the manually operable levers in advanced positions and means for permitting independent movement of said levers, the said means connected with the manually operable levers being also loosely connected with the stationary center post.

5. An apparatus of the character described comprising a base, trucks movable over the base, a center post fixed to the base and rising vertically therefrom, a bar revoluble upon the post and having connection with the

trucks, a tubular column surrounding the post and fixed to the bar, a gear fixed to 15 the column, a ratchet disk fixed to the post above the gear, oscillatory levers having toothed sectors meshing with the gear, members supporting the levers relatively to the gear and ratchet means carried by the supporting members and engageable with the ratchet disk.

10 In testimony whereof I affix my signature hereto.

STENGRIM ALSETH.
